ADJUSTABLE LOCK STRIKE

Arthur G. Lyons, Pennside, and William H. Sterrett, Reading, Pa., assignors to Reading Hardware Corporation, Reading, Pa., a corporation

Application October 15, 1932, Serial No. 638,006

3 Claims. (Cl. 292—340)

This invention relates to improvements in box strikes for locks and has particular reference to an improved adjustable metal keeper box for locks.

5 The primary object of this invention is the provision of an improved keeper box for the bolts of locks which is practical in construction and may with facility be adjusted to vary-
10 ing sizes in order that the same may be accurately set into place in a mortise of the door jamb, and so that a manufacturer need not carry a large variety of keeper boxes of different lengths to suit mortise locks of various sizes.

15 Other objects and advantages of this invention will be apparent during the course of the following detailed description.

In the accompanying drawing, forming a part of this specification, and wherein similar reference characters designate corresponding parts throughout the several views,

20 Figure 1 is a cross sectional view taken through a door jamb and adjacent closure in which a mortise lock is positioned showing in
25 the door jamb the improved adjustable box of the lock strike, adjusted to suit the size of the particular mortise lock used.

Figure 2 is a view similar to Figure 1 but showing the application of the same adjustable strike box to a mortise lock of smaller size than that shown in Figure 1.

30 Figure 3 is a perspective view showing an ex-
35 tended position of the two telescopically related members or sections making up the adjustable keeper box.

Figure 4 is a transverse sectional view taken through the box substantially on the line 4—4 of Figure 2.

In the drawing, wherein for the purpose of 40 illustration is shown only a preferred embodiment of the invention, the letter A may generally designate the improved adjustable keeper box adapted to be used in connection with a conventional strike plate B to make up the 45 keeper or lock strike construction which is mortised in the door jamb C. With this improved lock strike a mortise lock D located in the closure or door E may be used in the usual manner.

50 Referring to the adjustable box A, it is to be understood that it is within the contemplation of this invention to have the strike completely adjustable. However, in the example shown, the lock plate B is not adjustable. The box A pref-
55 erably consists of telescopically related sections

10 and 11. They each include a back wall 12 and side walls 13 and 14 and one end wall 15. The adjacent telescopically related ends of the sections 10 and 11 are open and the section 10 is adapted to be telescopically slid into the open end of the section 11 with the walls 13 of the section in abutment; the walls 12 of the sections in abutment, and the walls 14 of the sections in abutment. In order to prevent relative tipping of the box sections and to insure a 10 true rectilinear movement of the sections for accomplishing the sliding adjustment to the desired size, the side walls 13 and 14 of the section 11 are provided with internal ribs 20 ex-
15 tends from the open end of the section 11 along the said walls 13 and 14 for substantially over half the length of the section 11 parallel with and spaced from the inner surface of the wall 12. These ribs 20 are preferably stamped into the side walls; the entire box A being pref-
20 erably constructed of stamped sheet metal, al-
though the invention is not to be limited to any particular method of forming the box since cast metal boxes may be used in lieu of the stamped metal box. The side walls 13 and 14 of the box 25 section 10 are provided with grooves 21 upon the outer side surfaces thereof, and preferably for the entire length of the section 10, in spaced relation from the back wall 12 and paralleling the same so as to receive in complementary 30 manner the ribs 20 of the box section 11. Thus, when the sections 10 and 11 are assembled the ribs 20 slide in the grooves 21 and maintain the walls of the box sections in intimate sliding contact against relative tipping of the said sec-
35 tions. The end walls 15 of the box sections are of course provided with attaching flanges 25 with slots 26 opening at the ends thereof adapted to receive retaining screws or like elements by means of which the sections of the keeper box 40 are assembled upon the jamb.

A manufacturer of lock strike boxes is com-
45 pelled to have many varieties and sizes of strikes for different size locks. With the im-
proved adjustable keeper or strike box the prob-
lem for the manufacturer is materially simpli-
fied since in lieu of carrying in stock some fifty
or more sizes it will only be necessary to carry
three different width sizes; the length of the 50 box being adjustable for practically any height
or length of lock. For the installation the im-
proved adjustable lock strike box is an improve-
ment in that the same may be made to fit effi-
ciently in the mortise of the jamb and the 55

strike plate may be applied in proper relation thereto.

As to the assemblage the sections of the box are placed in the jamb cut-out or mortise as shown in Figures 1 and 2 of the drawing, and after application of the strike plate B the screws 30 will hold the box A in proper position. It is readily understandable that the lock plate may be made as part of the keeper box although we prefer to use a separate strike plate for each box in the manner shown in the drawing.

The parts of the lock strike box will not become disassembled during shipping and handling since the rib and groove construction of the sections enable them to be properly assembled in telescopic relation.

Various changes in the shape, size, and arrangement of parts may be made to the form of invention herein shown and described, without departing from the spirit of the invention or the scope of the following claims.

We claim:

1. A strike for locks comprising a box formed of a pair of complementary telescopedically connected sections having compartments communicating with each other and with both opening in the same direction, said sections at opposite ends thereof having outwardly extending attaching flanges provided with elongated slotted openings therein, a strike plate having bolt receiving openings therein and at the ends having screw receiving openings therein, and screws for extension through the last mentioned openings of the strike plate and through the

slotted openings of the box sections for attachment to a support for assembling the strike plate over the box sections with the latter held in definite relation.

2. A strike for locks comprising a pair of telescopedically connected box sections each having a rear wall, side walls and an end wall, the adjacent ends of the sections being open and the said box sections at the front being open in the same direction, means rearwardly of the front edges of said box sections connecting them for definite rectilinear sliding adjustment, all front edges of said sections lying in the same plane, a strike plate, and means for fixedly connecting the plate and the said box sections to a support with the plate in contact with the front edges of both of said box sections.

3. A mortise box for lock strikes and the like comprising a pair of telescopedically connected sections each having a rear wall, side walls, and one end wall, the adjacent ends of the sections being free of end walls and slidably connected together so that the size of the lock strike and the compartment thereof may be varied, the sections being open at the front to permit entrance of a lock bolt to the compartment thereof, said sections on the side walls rearwardly of the front edges having tongue and groove connections holding the same in non-tipping relation to permit rectilinear adjustment.
